UNITED STATES PATENT OFFICE.

MILTON C. HENLEY, OF NEW YORK, N. Y.

OIL-BURNER.

SPECIFICATION forming part of Letters Patent No. 726,059, dated April 21, 1903.

Application filed December 29, 1902. Serial No. 136,878. (No model.)

To all whom it may concern:

Be it known that I, MILTON C. HENLEY, a citizen of the United States, and a resident of the city of New York, borough of Manhattan, 5 in the county and State of New York, have invented a new and Improved Oil-Burner, of which the following is a full, clear, and exact description.

This invention relates to improvements in 10 burners for burning mixed oil and air in furnaces, stoves, ranges, and the like, the object being to provide a burner of simple and inexpensive construction so arranged that the gas will be quickly and uniformly generated and 15 a very hot flame obtained.

I will describe an oil-burner embodying my invention and then point out the novel features in the appended claim.

Reference is to be had to the accompanying 20 drawings, forming a part of this specification, in which similar characters of reference indicate corresponding parts in all the figures.

Figure 1 is a perspective view of an oil-burner embodying my invention. Fig. 2 is a 25 longitudinal section thereof, and Fig. 3 is a transverse section.

Referring to the drawings, 1 designates a spreader-bar, the sides of which are flared upward and outward, as indicated at 2. This 30 bar is provided with two longitudinal bores 3 4, which form generating-chambers, and to enlarge the heat-carrying capacity or area I place in each chamber a coiled rod 5. This coiled rod may be of spring material, if de- 35 sired, so as to engage closely against the end walls of the chambers. These end walls, as here shown, consist of screw-plugs 6, which may be removed for the purpose of moving the coil-rod or for cleaning purposes when 40 necessary.

From the chamber 3 at one end a tube 7 ex-

tends downward, and extended horizontally from this tube 7 is a burner-tube 8, provided with burner-nipples 9. A feed-tube 10 leads into the opposite end of the said chamber and 45 has communication through a small tube 11 with the oil-tank. From one end of the chamber 4 a pipe 12 leads downward and connects with a horizontally-disposed burner-tube 13, having nipples 14. These burner-tubes, of 50 course, are arranged directly under the spreader-bar. A feed-tube 15 leads into the opposite end of said chamber 4 and has a feed through a small tube 16. At the ends of the burner-tubes are screw-plugs 17, which may 55 be removed when it is necessary to clean out the tubes.

By employing two burner-tubes a very large flame is provided. It is also to be understood that the burner-tubes and the feed-pipes may 60 be formed in a single casting—that is, with a casting having two bores similar to the spreader-bar.

Having thus described my invention, I claim as new and desire to secure by Letters 65 Patent—

In an oil-burner, a chambered spreader-bar having its opposite sides flared upward and outward, a coiled rod arranged in the chamber, a feed-tube communicating with the 70 chamber at one end, and a burner-tube communicating with the chamber at the other end, the said burner-tube being extended along the under side of the spreader.

In testimony whereof I have signed my 75 name to this specification in the presence of two subscribing witnesses.

MILTON C. HENLEY.
